UNITED STATES PATENT OFFICE.

WILLIAM L. JONES, OF PHILADELPHIA, PENNSYLVANIA, ASSIGNOR TO VIBRO-DENTAL PRODUCTS, INCORPORATED, A CORPORATION OF PENNSYLVANIA.

DENTAL MASSAGE-TOOL.

1,340,959.

Specification of Letters Patent. Patented May 25, 1920.

Application filed August 14, 1916. Serial No. 114,717.

To all whom it may concern:

Be it known that I, WILLIAM L. JONES, a citizen of the United States, and resident of Philadelphia, county of Philadelphia, and 5 State of Pennsylvania, have invented an Improvement in Dental Massage-Tools, of which the following is a specification.

The object of my invention is to provide a dental tool for use with the usual hand 10 piece of a dental engine, by which said hand piece may be extended and provided with a reciprocating plunger for a massaging device suitable for massaging the gums, and means for transforming the rotary motion 15 of the mandrel of the ordinary hand piece into reciprocating movement of the plunger of the massaging tool.

My object is further, to form within the extra or extension hand piece, a spring actuated 20 massaging plunger and rotary means for reciprocating said plunger, the extension hand piece having engaging means for the usual hand piece of a dental engine and the rotary means having an extension to be 25 received in and detachably clamped in the tool chuck of the said usual hand piece.

My object is also to provide a massaging tool for a dental engine which shall be light 30 in construction, simple, inexpensive and readily capable of being dismantled for access to the operative parts.

With the foregoing objects in view, and others referred to hereinafter, my invention consists in certain constructions and combinations of parts which are fully described 35 in the following specification and more particularly recited in the claim.

My invention will be better understood by reference to the drawings, in which:—Figure 40 1 is an elevation of a dental tool holder with my improved massaging tool applied thereto; and Fig. 2 is a sectional view of a portion of the same on a larger scale.

1 is the usual hand piece of a dental engine and is provided with the rotary chuck 2 of any suitable construction, said chuck journaled in the hand piece and driven by a belt (not shown) passing about the grooved wheel 3 on the chuck spindle. The part 4 45 constitutes the usual wrist joint of the jointed arm of the dental engine, and guides the belt about the grooved wheel 3. The chuck may be adjusted to clamp the tool by the adjusting milled head 5, as usual. These parts 50 are shown by way of example only, as the

chuck may be driven by a flexible shaft as is more common in electrically operated dental engines.

The massaging tool embodying my invention has a casing constituting an extension 60 of the hand piece 1 and comprises a sleeve 6 screwed upon a neck 8 having the case 9, terminating in the plunger chamber 14. The sleeve 6 fits over the end of the hand piece 1 back of the chuck 2, and has a slot 6^a 65 in which a screw head 6^b on the hand piece is received (Fig. 2), and in this way is held against turning. The neck part 8 constitutes a bearing for the rotary spindle 7 whose rear extension projects through the 70 sleeve 6 and is received in the chuck 2 and clamped therein, whereby it may be rotated with the chuck. The other end of the spindle 7 is fitted with a disk 10 secured at an oblique angle to the axis of the spindle, this 75 disk being greater in its oblique diameter than in its transverse diameter, so that its perimeter may be concentric to the axis of the spindle 7. This disk 10 is arranged 80 within the body of case 9 and is rotated therein by the chuck.

The plunger chamber 14 preferably tapers and has its larger end provided with a cylindrical hub 14^a which fits into the case 9 and is secured thereto by screws 18. The 85 other or smaller end of the plunger chamber 14 is internally screw threaded and fitted with a bushing 17 which also constitutes a bearing for the reciprocating plunger 12. The lower end of the plunger 12 is arranged 90 to reciprocate in the hub 14^a as a bearing, and is provided with a collar or flange 12^b which limits the inward stroke of the plunger. A coil spring 13 surrounds the plunger, one end pressing upon the annular collar or flange 12^b and the other end pressing 95 against the inner end of the bushing 17. In this way, the plunger 12 is spring pressed inwardly, but it is provided on its end with a bent finger 11, the lower end of which is 100 rounded and fits to the surface of the rotating disk 10 near its perimeter so that said disk imparts to the plunger an intermittent outward movement in opposition to the spring's action. To prevent the plunger rotating, it is provided with a longitudinal 105 groove 12^c in which one of the screws 18 fits. It will now be understood that as the spindle 7 and disk 10 rotate, the cam action of the latter upon the finger or plunger ex- 110

tension 11 causes said plunger to have a rapid reciprocation. This reciprocation is in a positive manner in the outward thrust, but yielding under the spring action on the 5 inward movement.

The outer end of the plunger 12 is bored and screw threaded, and receives the threaded end of the shank 15 of the massaging device 16, said shank 15 preferably being of a 10 diameter equal to that of the plunger, and the end of the bushing extending beyond the part 14 to provide a shield to the joint between the plunger and shank. The massaging device shown is a rubber cup, but the 15 shape of this part may be varied to suit the character of massage to be given to the gums.

The general construction of the casing of the massage tool may be modified, but as 20 shown it is easily separated into parts so that all the operative portions may be removed and repaired and said casing becomes an extension to the hand piece of the engine being held against rotation thereon and 25 clamped to it by the engagement of the shank or rear extension of the spindle 7 in the chuck 2 of the hand piece.

I have shown my invention in the form which I have employed in practice and 30 which I have found well suited to the purposes intended; and while I prefer the same,

I do not restrict myself to the details thereof, as these may be varied and modified without departing from the spirit or scope of the invention.

35

Having now described my invention, what I claim as new and desire to secure by Letters Patent, is:—

In a device of the character stated, an extension hand piece arranged for being detachably connected with the usual hand piece and rotary chuck of a dental engine, combined with a rotary spindle in the extension hand piece having an extension for engagement in the chuck, a reciprocating 45 plunger in the free end of the extension hand piece provided with a tool holding end, a spring continually tending to force the plunger inward, means within the extension hand piece for imparting a positive reciprocating motion outward and a controlled inward movement to the plunger, said means actuated by the rotary motion of the spindle, and means to hold the plunger against rotation.

50

In testimony of which invention, I hereunto set my hand.

WILLIAM L. JONES.
